UNITED STATES PATENT OFFICE.

EVAN J. GRIFFITH, OF OSAGE, WYOMING.

OIL BURNER.

Application filed July 11, 1921. Serial No. 423,920.

To all whom it may concern:

Be it known that I, EVAN J. GRIFFITH, a citizen of the United States, residing at Osage, in the county of Weston and State of Wyoming, have invented certain new and useful Improvements in Oil Burners, of which the following is a specification.

This invention relates to oil burners for furnaces, boilers, and the like, and the primary objects of the present invention, are, first to provide in a burner a novel means for facilitating and insuring the thorough mixing and intermingling of the fuel and steam; second, to provide a novel arrangement of the burner outlets, so as to insure proper drainage of the burner, and to readily permit the cleaning of the burner and burner outlets by steam pressure when so desired; and, third, to provide a novel means for introducing and controlling the inlet of the oil and steam to the burner.

A still further object of the invention is to provide a burner of this character, which will be durable and efficient in use, one that will be simple and easy to manufacture, and one which can be readily placed upon the market and incorporated with a furnace or boiler at a small cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a side elevation of the improved burner showing the same in operative position in relation to a boiler, the boiler being shown in vertical section.

Figure 2 is a top plan view of the improved burner in operative position in relation to a furnace, the furnace being shown in horizontal section.

Figure 3 is an enlarged horizontal section through the improved burner.

Figure 4 is a fragmentary bottom plan view thereof.

Figure 5 is a detail transverse section through the body portion of the burner.

Referring to the drawings in detail, wherein similar reference characters designate corresponding parts throughout the several views, the letter A indicates the improved burner; B, the means for introducing the fuel and steam thereto; and C a furnace, with which it is associated.

The furnace or boiler C may be of the usual or any preferred construction, and has been merely shown for illustrating the use of the improved burner, and the relation of the improved burner thereto, when the same is in actual use. As shown the furnace or boiler includes the fire box 10 and the boiler 11, which is provided with a plurality of flues 12. If so desired, the fire box 10 may have a heap of loosely piled fire brick therein against which the flame of the burner can be projected. As shown, the heap of fire brick has been designated by the numeral 13. The front wall of the fire box is provided with the usual opening 14.

The burner A includes a longitudinally disposed inner tube 15, which has its opposite ends communicating with the inclined branch pipes 16 and 17, which terminate in a single feed pipe 18. The inner tube 15 is disposed axially in a relatively large tubular casing 19, which has its opposite ends closed by end walls 20. As shown the branch pipes 16 and 17 project rearwardly through the tubular casing 19. The inner tube 15 is provided with spaced rows of annularly arranged longitudinally extending slots 21, and if so desired, the slots of each row may be arranged in staggered relation to each other.

The tubular casing 19 forms the mixing and cracking chamber for the steam and oil, and the arrangement of the slots 21 in the inner tube 15 insures that the oil and steam will be directed into all portions of the casing in order that the oil and steam will be thoroughly intermingled, and to permit each burner tube, designated by the numeral 22, to receive its full share of the combustible mixture.

The burner tubes 22 are spaced equidistantly along the casing 19, and project tangentially from the lower surface of the casing thus insuring the proper drainage of the burner and casing and permitting the ready cleaning of the burner by steam pressure. If so desired, these burners may have their bores contracted as at 23 in order to throw the flame into the furnace toward the fire brick and flue tubes 12.

If so desired, the burner tubes may be inclined, so as to project the flame toward the central portion of the boiler in order to prevent the burning of the fire side plates of the fire box of the furnace, when a relatively narrow furnace is being used with the

burner. This has been clearly shown in Figure 4 of the drawings.

The means B for introducing oil and steam into the burners A comprises a pipe system 25, which has communicating therewith intermediate its ends a steam pipe 26, which can be provided with a suitable hand operated valve 27. The pipe system 25 in rear of the steam pipe 26 is provided with the oil or fuel pipe 28, and this pipe is also provided with a suitable hand operated valve 29 for controlling the flow of the oil or fuel into the pipe line 25. Thus it can be seen that the amount of oil and steam can be readily controlled independent of each other by means of the valves 27 and 29. A valve 30 of the globe or other hand operated type is arranged in the line 25 forwardly of the steam and oil pipes, and forms means for controlling the flow of oil and steam into the line or feed pipe 18.

As clearly shown in Figures 1 and 2 of the drawings, the burner A is placed in the fire box 10 through the door opening 14, and is arranged in such a manner as to permit the flame from the burner tubes 22 to be directed toward the fire tubes 12, and the loosely piled heap of fire brick 13.

By this arrangement of the burner tubes or nipples 22 on the casing 19, it can be seen that a perfect drainage of the burner can be had in order to prevent any sediment or condensation to stand therein, and it can be seen that when it is desired to clean the burner or the fire tubes, that it is merely necessary to close off the valve 29 and open the valves 27 and 30, and the steam pressure will readily force all obstructions or foreign matter from the burner and the burner tubes or nipples.

From the foregoing description, it can be seen that an exceptionally simple and durable burner has been provided, in which the oil and steam will be thoroughly intermingled and forced directly into the fire box of the furnace, in such a manner that all of the fuel will be used, and that sediment and condensation will be drained from the burner.

Changes in details may be made without departing from the spirit or scope of this invention; but,

I claim:

1. An oil burner comprising a longitudinally extending casing, a longitudinally extending inner tube disposed axially within the casing and spaced at all points from the walls thereof, means for introducing a combustible mixture into the inner tube, the tube being provided with a plurality of spaced slots arranged in annular formation at spaced points throughout the length thereof, to permit the mixture to flow into

the casing at different points, and burner nipples carried by the casing.

2. A burner comprising a casing, a longitudinally extending axially disposed inner tube arranged within the casing, means for introducing oil and steam into the inner tube, the inner tube having a plurality of spaced annularly disposed rows of slots formed therein and extending throughout the length thereof for permitting the mixture to flow into all parts of the casing, and a plurality of outwardly extending nipples carried by the casing and arranged intermediate the spaced annular disposed rows of slots.

3. An oil burner comprising a longitudinally extending casing, a longitudinally arranged axially disposed inner tube arranged in the casing, a feed pipe, branch pipes extending from the feed pipe and communicating with the ends of the inner tube, the inner tube having a plurality of slots formed therein, and a plurality of spaced burner nipples carried by the casing and extending tangentially therefrom at the lower end thereof.

4. An oil burner comprising a tubular casing, a longitudinally extending axially disposed inner tube arranged within the casing, a feed pipe, branch pipes communicating with the feed pipe and with the terminals of the inner tube, the inner tube having spaced rows of annularly arranged slots formed therein, the slots of the rows being arranged intermediate each other, and a plurality of tangentially extending burner nipples formed on the casing and projecting forwardly from the lower end thereof, the nipples being arranged intermediate the rows of the longitudinally extending annularly disposed slots.

5. In a burner, a body, an inner tube arranged in the body having a plurality of radially extending longitudinally disposed slots, a plurality of burner nipples formed on the casing, a feed pipe, branch pipes communicating with the feed pipe and with the terminals of the inner tube, a line pipe, means connecting the line pipe with the feed pipes, and a steam feed pipe communicating with the line pipe, an oil pipe communicating with the line pipe in rear of the steam pipe, and valves arranged in the steam pipe and oil pipe, and a valve in the line pipe arranged forwardly of the oil and steam pipes.

6. In an oil burner, a cylindrical casing, a cylindrical axially disposed inner tube arranged in the casing having distributor slots formed therein, and a plurality of burner nipples carried by the casing and extending tangentially from the extreme lower end thereof.

EVAN J. GRIFFITH.
